UNITED STATES PATENT OFFICE.

REGINALD A. FESSENDEN, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

ELECTRIC SIGNALING.

1,179,906.

Specification of Letters Patent. Patented Apr. 18, 1916.

Application filed June 16, 1908. Serial No. 438,725.

To all whom it may concern:

Be it known that I, REGINALD A. FESSENDEN, a citizen of the United States, residing at Brant Rock, in the county of Plymouth and State of Massachusetts, have invented 5 certain new and useful Improvements in Electric Signaling, of which the following is a specification.

My invention relates to the receipt and 10 transmission of electrical signals and more particularly to wireless signaling. Its primary object is a more efficient transmission and receipt of electrical signals, more particularly wireless signals, and the recording 15 of such signals. Other advantages and objects will hereinafter appear.

The invention is illustrated in the accompanying drawings forming a part of this specification wherein.—

20 Figures 1 and 2 show respectively in section and plan a wireless telegraph receiver in which motion is used to alter the resistance of a microphonic cell, instead of directly producing a sound indication, and 25 Figs. 3 and 4 are respectively a cross section and a plan of a form of receiver in which the static attraction is used to produce a change in the resistance of a local microphonic circuit, Fig. 3 showing also a diagram of circuits.

Dolbear in U. S. Patent No. 350,299 of 1882, described a static telephone receiver, invented by him for receiving wireless signals, and this receiver has been used by other 35 experimenters for the same purpose.

In the various forms used the diaphragms have been made of sheet metal or of sheet metal covered with an electrified dielectric, or of a dielectric with a metallic coating on 40 the side next the fixed plate. These types of receivers have on this account been too insensitive, and have not come into practical use.

I have discovered that by the use of certain improved constructions and improved 45 methods of operation, static receivers can be made which are more sensitive even than the liquid barretter, as determined by actual tests under practical working conditions, 50 and I have herein shown several arrangements by which this result is attained.

In Fig. 1, I use two pieces of thin mica 59 and 60, to which are fastened two pieces of platinum foil 61 and 62, suspended by

two wires 63 and 64 from a terminal 65, so 55 that when the terminal is connected to an electrified source, the flat pieces of platinum foil 61 and 62 will be repelled from each other. They depend into a trough 66 with electrodes 67 and 68 connected to terminals 60 69 and 70; and the trough contains a charge of microphonic carbon 71. On the plates 61 and 62 being repelled the resistance between the electrodes 67 and 68 and the pieces of platinum foil 61 and 62 is altered, and 65 affects the current as in the well-known telephone transmitter. The device acts as an amplifier. In Fig. 2 is shown another form of this device or amplifier. Here a number of pieces of platinum foil 72, 72, 70 are connected to one binding post, 73, and interleaved with a number of other pieces of platinum foil 74, 74 connected to a second binding post 75. Between the sets of foil are pieces of sheet mica 76, and layers of 75 microphonic carbon 77. There are also screws 78, 79 for adjusting the pressure of the amplifier.

In Figs. 3 and 4 is shown another form of amplifier. Here 91 is a fixed plate mounted 80 so as to be adjustable by means of the milled screw 92, and covered with a coating of mica 93. On an insulating support 95 is mounted a diaphragm or thin plate 94, and to support 95 is also fastened another plate 85 or spade 96 dipping in a trough 97 having two electrodes 98 and 99 and filled with a mass of microphonic carbon 100. Attached to the insulating piece 95 are wires 101 and 102, mounted in frame 104 and made adjustable as to tension by means of the knurled nut 103 (Fig. 4). The connections being as per the diagram, Fig. 3, for operation, the electrical waves cause electrical oscillations to flow from the antenna 105 95 through the primary 106 of a transformer to ground at 115, thereby producing oscillations in the secondary 107 and the circuit including also a variable inductance 108, and a capacity formed by the plates 94 and 91. 100 The electrostatic attraction thereby produced between these plates sets the plate 94 in motion and, therefore, also the spade 96, projecting in the carbon. This varies the resistance in the local microphonic circuits 105 containing the battery 109, the primaries 110 and 111 and the microphonic carbon 100. Electric impulses are thereby produced in

the secondary 112 which cause a sound in the telephone receiver 113 in circuit therewith.

Having thus described my invention and 5 illustrated its use, what I claim as new and desire to secure by Letters Patent, is the following:

1. A receiver for wireless telegraphy comprising a movable mica diaphragm, a platinum leaf thereon, a fixed plate statically attracted by said movable plate, a microphonic material between the movable and fixed plates, whereby the motion of the movable plate may be indicated by variation 10 of resistance of said microphonic material.

2. A receiver for wireless telegraphy, comprising a movable diaphragm, a fixed plate statically attracted by said movable diaphragm, and a microphonic material be-

tween said plate and diaphragm, whereby 20 movement of the movable diaphragm varies the resistance of the microphonic material.

3. A receiver for wireless telegraphy, comprising a movable diaphragm, a fixed plate on either side of said diaphragm and 25 statically attracted thereby, and a microphonic material between said diaphragm and plates, whereby movement of the movable diaphragm varies the resistance of the microphonic material.

In testimony whereof I have hereunder signed my name in the presence of the two 30 subscribed witnesses.

REGINALD A. FESSENDEN.
